CAN OPENER

Harry L. Dazey, St. Louis, Mo., assignor to Dazey
Churn & Manufacturing Co., St. Louis, Mo., a
corporation of Missouri

Application August 16, 1934, Serial No. 740,098

4 Claims.

(Cl. 30—3)

This invention relates to can openers, and more particularly to an improved blade mounting especially applicable for can openers of the type employing a feeder roll for advancing the unsevered metal toward the blade.

An object of the present invention lies in the provision of an improved mounting for the can opener blade, or cutter element which facilitates the operation of the device, particularly when operating on the can metal adjacent a seam or other irregularity in the bead or rim of the can.

Another object of the invention is to provide, in a can opener, a blade element which adjusts itself to irregularities, such as seams or dents in the can wall, and thereby is adapted to sever the metal extremely close to an adjacent wall portion even though such adjacent wall portion contains a seam or other irregularity. This feature is very desirable, since, when a can is opened by the present device, no sharp projections remain as a part of the container to cut or otherwise injure the user.

The foregoing objectives are attained by the provision of an improved blade mounting which permits the blade to yield sufficiently to pass an enlarged or irregular portion of the bead adjacent to which the blade may be operating.

A further object lies in the provision of an improved mechanism for holding a container in proper operative engagement with the feeder roll.

Other objects and advantages will appear from the following description and drawings wherein:

Fig. 1 is a side elevation of the device of my invention; Fig. 2 is a fragmental plan view illustrating means for attaching the device to a supporting structure; Fig. 3 is a fragmental side elevation showing parts of the operating mechanism as viewed from the side opposite to the view of Fig. 1; Fig. 4 is a fragmental side elevation with the actuating handle for the roller removed; Fig. 5 is an end view of the device; Fig. 6 is a sectional elevation taken at line 6—6 of Fig. 4, and Fig. 7 is a sectional plan view taken at line 7—7 of Fig. 1, showing the "hold-down" device.

Referring now by characters of reference to the drawings, the operating mechanism of the device is preferably mounted on a flat, substantially rectangular base plate 10 which is arranged to be removably secured to a wall or other supporting structure by the means illustrated in Figs. 1 and 2. Such means are fully described in U. S. Letters Patent to T. A. Killman, No. Re. 16,957, dated May 8, 1928, and briefly, include a trapeziform plate 11, secured at right angles to

the base plate 10 at one end thereof. Plate 11 is adapted to be wedged between relatively converging channels 12 formed at opposite edges of a bracket plate 13 which may be permanently fastened to a wall or other support as by means of screws 14.

Describing now the means for supporting the can and feeding the can metal into cutting engagement with the blade, the base plate 10 is provided near its outer or free end with a circular aperture in which is journaled a disc 15 (Fig. 6), of thickness approximating that of the base plate 10. The disc 15 is held for rotation in the aforesaid aperture between discs 16 and 17, which are of greater diameter than, 15 and disposed concentric with disc 15. The disc 17 is provided with a radial projection forming a handle 18, and rotation of disc 17, as by means of handle 18, is imparted to the disc 15 and 16 which are fixed for rotation with disc 17. Joint 20 rotation of the said discs is secured by forming an aperture in disc 15, and upsetting or punching the discs 16 and 17 to cause the metal thereof to enter such aperture, all of which is indicated at 19. Eccentrically disposed relative to the disc assembly, and projecting transversely therethrough, is an externally threaded sleeve 20 in which is journaled the feeder roll shaft 21. The sleeve 20 is fixed to the discs 15, 16 and 17, and secures the same together between a collar 22, integral with the sleeve, and a nut 23, threaded on the sleeve. The shaft 21 terminates at one end in the feed roll 24, consisting of a hard metal disc having a toothed peripheral surface, the roll 24 being suitably fixed for rotation by 35 the shaft 21. A crank 25, keyed to the opposite end of the shaft and secured thereto by a nut 26, serves manually to drive the feed roll 24.

Describing now, an improved "hold down" mechanism which operates to maintain a can 40 in operating engagement with the feed roll, such mechanism embodies an arm 27 which is pivotally connected at one end to the base plate 10 through the agency of a stub shaft 28 projecting laterally from the plane of the base plate. The 45 arm 27 is bent laterally, forming a portion 29 thereof which overlies the feed roll 24, and such portion of the arm is arranged for spring-biased movement toward and from the feed roll. Pivotal movement of arm 27 in a direction away 50 from the feed wheel is yieldingly resisted by a leaf spring 30, one end of which is secured to the stub shaft 28, the opposite end bearing upon portion 29 of the "hold down" arm. A stud 31, projecting from the base plate 10 and spaced from 55

the stub shaft 28, engages the leaf spring and maintains the same in stressed condition against the arm portion 29. The disc 16 provides a stop for the arm 27, limiting its range of movement 5 toward the feed roll. The arm portion 29 is provided with a recess 32 through which a blade, or cutter element 33 projects, the arm thereby serving as a guard which effectually prevents a user from injuring himself on the sharp portion 10 of the blade.

Describing now the blade element and mounting therefor, such mounting includes a U-shaped bracket 34, secured to the base plate 10 as by rivets 35. Journalled for pivotal movement on 15 a pin 36 which extends between and across the leg portions 37 of bracket 34 is a saddle element 38, to which element is secured, as by rivets 39, the blade 33. By preference the blade element 33 comprises a horse-shoe magnet, the rivets 39 extending through one leg portion 40 thereof of which leg portion is of greater length than its companion portion 41, the end of leg portion 40 being suitably sharpened to provide a cutting edge. From Fig. 6 it will appear that blade 25 portion 40 of the magnet lies in a plane parallel to the plane of the outer end face of feed roll 24, and is spaced outwardly from such end face a distance approximating the width of the sealing bead 42 which is provided on all containers of 30 conventional type. The magnet portion 41 extends to a point adjacent the cutting portion of the blade, and with such latter portion attracts and retains any metal fragments which may be severed during a cutting operation.

35 The lower, or cutting end of blade portion 41 is adapted to rock in a clockwise direction (Fig. 6) from a normal, limit position in which such blade portion is disposed at right angles to the axis of the feed roll. It will appear that movement of the blade element in the direction specified increases the spacing of the blade and feed roll. The normal operating position of the blade member is fixed by stop lugs 43 projecting upwardly from the bracket 34, which lugs form 40 abutments for laterally projecting ears 44 on the saddle 38. The saddle is urged into its normal position wherein ears 44 abut lugs 43, by a spring 45, which may be of any suitable type. In the present example, a substantial U-shaped leaf 45 spring is employed, opposite ends of such spring being secured to the bracket and saddle members by rivets 35 and 39, respectively.

The handle 18, by which the position of the feed wheel relative to the blade is adjusted 55 (through the agency of the eccentric mounting for the feed roll shaft) has two major positions. Preparatory to introducing a can into the device, the handle 18 is moved to the position shown in Figs. 1 and 5. When in such position the upper peripheral surface of the feed wheel is spaced downwardly from the lower extremity of the blade to permit the sealing bead on the can to be inserted therebetween. With the toothed surface 60 of the feed roll engaging the sealing bead, the handle 18 is turned through 180° causing the feed wheel, and hence the can, to be moved toward the blade, and causing the blade to penetrate the container (Fig. 6) at a point immediately adjacent the inner surface of the bead. 65 The container is held in frictional engagement with the toothed surface of the feed roll by the "hold down" arm 27 which presses upon the upper edge of the container head, as previously described. When in full open, or can-receiving condition, (Figs. 1 and 5), a stop shoulder 46 on the 70

handle 18 abuts a stud 47 projecting from the base plate 10, such shoulder and stud cooperating to determine the position of handle 18 when the device is in open condition. Another stop shoulder 48 on the handle cooperates with a stud 49 5 projecting from the base plate to determine the handle position when the device is in condition for operation on a container. Means for temporarily locking the device in the latter condition are provided, and in the present example 10 such means include a recess in the handle which is adapted to seat a boss formed on the base plate 10, both indicated at 50 (Fig. 6).

Rotation of the crank 25 is imparted to the container through the medium of the feed roll, 15 such rotation of the can relative to the blade producing the desired results, or that of severing the top wall from the container body. A lug portion 51, projecting laterally from the base plate 10 for engagement with the side wall of the container, aids in maintaining the container in proper position for cutting, and further, prevents vibration of the container which might occur during the cutting operation. In the event that the blade element encounters an obstruction during the cutting operation, such as a seam, dent or other agency forming a transverse enlargement of the bead, instead of cutting through such obstruction the blade is caused to rock, to increase its spacing relative to the feed roll, and thereby operates on the can wall clear of any deformation which would otherwise tend unduly to retard the operation of the blade. Otherwise expressed, by reason of the described blade mounting, the blade is adapted to follow closely 25 the contour of the inner periphery of the sealing bead, adjusting itself to any irregularities 30 encountered therein during its course of operation. Irregularities in the vertical, or axial dimensions of the bead are compensated for by the 35 yieldable hold down arm.

It will thus appear that the device of my invention is adapted to operate smoothly and easily, despite irregularities in the periphery of the container. While a can opener blade of magnetic 45 type is herein shown and described, obviously any other suitable type of blade may be employed. Since other variations may be effected, without departing from the scope of my invention, I do not wish to be limited to the exemplary construction herein shown and described, except as defined by the following claims.

I claim:

1. A can opener including in combination a base plate, a blade spaced from the plane of the base plate, a feeder roll mounted for rotation in a plane between said blade and base plate, and means 55 rockingly mounting said blade on the base plate, including laterally projecting elements on said base plate and blade, and a pin pivotally connecting said elements, the blade being thereby adapted to rock in a direction away from the feeder roll.

2. A can opener including in combination a base plate, a blade disposed laterally of the base plate, 65 a feeder roll mounted for rotation in a plane intermediate the blade and base plate, and means for mounting the blade for rocking movement relative to the feed roll, said means including a bracket secured to the base plate, a projection on 70 said blade, a pin pivotally connecting said projection and bracket, means forming a limit stop, defining a normal cutting position of the blade relative to the feeder roll, and a spring adapted yieldingly to hold the blade in normal position. 75

3. A can opener including in combination a base plate, a feeder roll spaced laterally of the base plate, a yieldable spring-biased arm overlying the feeder roll, adapted to hold a can in operative engagement with the feeder roll, a blade element projecting toward the feeder roll, through a recess in said arm, and means mounting said blade element projecting toward the feeder roll, through a recess in said arm, and means mounting said blade element for rocking movement in a plane parallel to the axis of the feed roll.

10 4. A can opener including in combination a

base plate, a feeder roll spaced laterally of the base plate, a yieldable, spring-biased arm overlying the feeder roll adapted to hold a can in operative engagement therewith, a blade element projecting through a recess in the said arm, toward said feeder roll, means mounting said blade element for rocking movement in a plane parallel to the axis of the feeder roll, and a spring disposed to resist rocking movement of the blade.
